10 Claims.

(Cl. 73—51)

This invention relates to a machine for obtaining facts quantitatively determinative of the mass change necessary in a body to balance it while rotating.

5   Vibration in a machine is often caused by an unbalance in a rotor therein. This unbalance is due to unequilibrated centrifugal forces generated in the rotor. The unbalanced centrifugal force may act only radially from the axis of rotation and substantially uniformly along that axis. This condition is known as pure static unbalance. Pure static unbalance causes a translatory motion of the axis of rotation of the rotor to a new position parallel to its initial position. 10   The unbalanced centrifugal forces may act only at a right angle to a longitudinal line drawn through the center of mass of the body, and be equal in opposite directions, that is, additive in effect, on both sides of the center. This unbalance is known as pure dynamic unbalance. Pure dynamic unbalance causes a pivoting of the axis of rotation upon an axis at a right angle thereto and positioned intermediate the ends of the body.

A body rotatable upon a longitudinal axis is 25 perhaps seldom encountered which is in unbalance due to either pure static or pure dynamic unbalance. If the major effect of the unbalance makes it appear as though the body were statically unbalanced there is almost always an effect which makes it appear that the body is 30 dynamically unbalanced. This probably generally arises from the fact that the mass causing what appears to be a major effect of static unbalance does not lie exactly in the transverse plane of the center of gravity or mass of the body. When the major effect is as though the body were 35 dynamically unbalanced there is also generally an effect which makes it appear that the body is statically unbalanced. This generally arises from the fact that the unbalanced centrifugal forces are not exactly equal and opposite on both sides of the axis of rotation. This excess of mass on one side of the axis of rotation causes an effect which appears and is a static unbalance.

In view of the above stated facts it is believed 40 best to apply the term static unbalance only to cases of pure static unbalance and to apply the term dynamic unbalance only to cases of pure unbalance to designate a condition in which the body exhibits a motion when rotated which makes it appear as though it is unbalanced both statically and dynamically. In the practical art 45 the condition which I designate by general un-

balance has perhaps, unfortunately, become known as dynamic unbalance.

The word alpha as used in this specification, defines that component of unbalance in a body which tends to make the body oscillate only about an axis parallel to its axis of rotation when rotated about its longitudinal axis and so supported that it may oscillate as a whole, which oscillation is caused by a static unbalance.

The word beta as used in this specification, defines that component of unbalance in a body which tends to make the body oscillate only about an axis at a right angle to its axis of rotation when rotated about its longitudinal axis and so supported that it may oscillate as a whole, which oscillation may be caused either by a static or a dynamic unbalance or by a combination of both.

Alpha and beta components together define the tendency of a body to rotate about an axis other than the actual axis of rotation.

Magnitudes corresponding to these two different tendencies completely define values of masses which must be added to the body to completely correct the tendencies.

Correction for unbalance requires subjection of the rotor to tests which indicate the necessary mass change in the rotor.

A principal object of applicant's invention is the provision of a machine by which the magnitude of the alpha component and the magnitude of the beta component, may be ascertained by tests applied to the rotor, and then may be assigned, as a matter of computation, to such positions on the rotor that either one if actually applied would not interfere with the inherent unbalance in the rotor due to the other.

Another object of the invention is the provision of a machine by which magnitudes, one representing the alpha component the other the beta component, are obtained which are assigned, as a matter of computation, in such a way, that the computation of the magnitude of a single mass change as a resultant in a given plane is facilitated.

A further object of the invention is to provide a machine whereby magnitudes are obtained whereby the computation to assign the proper position of portions of the alpha magnitude and portions of beta magnitude is simplified.

A further object of the invention is the provision of a machine by which the general unbalance may be ascertained as two numerical quantities, one of which may be considered alpha unbalance, that is, one component of unbalance; and the

other may be considered as beta unbalance, that is, another component of unbalance.

A further object of the invention is the provision of a machine which preferably, although not necessarily, simultaneously indicates or registers both desired numerical quantities determinative of unbalance without a repositioning of the rotor or mechanical manipulation to separate the effects of the two kinds of unbalance.

10 Other objects and advantages of the invention will appear as the description of a particular physical embodiment of machine proceeds, and the novel features of the invention will be particularly pointed out in the appended claims.

15 The fundamental discovery, the basis of applicant's machine is that correction for alpha unbalance may be so applied that it will have no effect upon the inherent beta unbalance of a body, and correction for beta unbalance may be 20 so applied that it will have no effect upon the inherent beta unbalance of the body, and in order to thus practically and conveniently apply those corrections they must be distributed in at least two transverse planes of the body, one on each 25 side of the vertical plane containing the axis by which the beta component of unbalance is obtained. The correction for alpha unbalance must be applied all on one side of the longitudinal axis of rotation and distributed between the planes so 30 as to generate centrifugal forces which collectively are equal and opposite to the inherent alpha unbalance and also so as to generate centrifugal forces balanced about the beta axis. The correction for beta unbalance must be applied on opposition 35 site radii from the longitudinal axis of rotation, partly on each side of the vertical plane through the beta axis of a magnitude and position, as regards the beta axis so as to produce a couple of centrifugal forces equal and opposite in effect to the 40 couple which causes the beta unbalance, and also so as to generate equal and opposite centrifugal forces about the longitudinal axis of rotation.

45 Applicant's invention is characterized by a principle which requires restrained oscillation of the rotor on each of two axes. One of the axes is parallel to the axis of rotation of the rotor. Oscillation on this axis ascertains the numerical quantity determinative of the alpha unbalance.

50 The other oscillation axis is at a right angle to the first and lies in a plane transverse to the longitudinal axis of rotation of the rotor. Oscillation on this last mentioned axis ascertains the numerical quantity which is determinative of the 55 beta unbalance of the rotor.

It is to be observed that applicant has not narrowed the specification of the axes, in that, the axis employed to obtain the alpha component has not been specified as necessarily lying in a vertical 60 plane passing through the axis of rotation of the rotor, because such axis may correspond to and take all positions of the generatrix of a right cylinder, the axis of which coincides with the longitudinal axis of rotation of the body; and the 65 axis associated with the beta component has not been specified as necessarily lying in the vertical plane cutting the longitudinal axis of rotation and midway of the body, because it is evident, that this axis may lie anywhere in any vertical 70 plane, transverse to the axis of rotation of the rotor between the planes of correction.

75 Applicant's invention is further characterized by a principle which requires that the mass change ascertained from the numerical quantity determinative of the alpha unbalance shall be

distributed or assigned in such manner that the resulting mass change in the rotor will have no effect upon the beta unbalance already existing therein. This requirement necessitates applying the correction mass for the alpha unbalance all 5 on one side of the longitudinal axis of rotation of the body and in at least two planes, one on each side of the longitudinal center of the body. It further requires that the amount on one side of the axis by which the beta magnitude is ascertained shall be proportioned so that it will generate a moment about that axis equal to the moment generated by the amount on the other side and opposite in effect. This requirement of equal moments generally necessitates a knowledge 10 as to the distance of each correction plane from the axis, that is, the axis at a right angle to the longitudinal axis of rotation of the body, upon which the body oscillates when the numerical quantity determinative of the beta unbalance is 15 being ascertained, although it is not to be understood by this statement, that one must necessarily know as a numerical quantity the linear distance of the correction plane from the axis, because by calibrating a given machine employing 20 a given rotor with known unbalance therein a ratio may be ascertained which will equal the ratio of the linear distances, if they were known. 25

It is evident, then, that in order not to disturb beta unbalance when correcting for alpha unbalance, the correction mass applied by applicant must be applied all on one side of the longitudinal axis of rotation and in a numerical amount equal to the numerical value of the alpha unbalance but in each correction plane inversely as the 30 distance of that correction plane from the axis upon which the body oscillates when the numerical quantity determinative of beta unbalance is ascertained, and so as to generate equal moments 35 about the beta axis.

40 Applicant's invention further requires that the correction applied for beta unbalance shall be applied to the body in such a way that it will not disturb alpha unbalance. This requires that the mass change necessary for correction for beta unbalance shall be divided between at least two planes one on each side of the beta axis, and the masses 180 degrees apart as regards angular rotation in a plane transverse to the longitudinal axis of rotation, and positioned so that equal 45 and opposite centrifugal forces about the longitudinal axis of rotation are generated.

50 Correction for beta unbalance may be made in any two transverse planes of the rotor but if it is not made in the same planes in which the 55 correction for alpha unbalance is made the absolute magnitude must be altered so that it will generate the same moments, as it would have generated if it had been placed in those planes, about a given point, that is, the point of intersection of the longitudinal axis of rotation with the transverse vertical plane passing through the axis upon which the oscillation took place for determining the beta correction, that is, in all cases it must generate a couple of centrifugal 60 forces equal and opposite to the couple of centrifugal forces causing beta unbalance.

65 If correction for alpha unbalance is to be made in one pair of planes and correction for beta unbalance in another pair of planes the general 70 relation above pointed out must still subsist, that is, the alpha correction must be so made that it will not disturb the beta unbalance, that is, will generate equal and opposite, that is, an algebraic sum of zero turning moments, about the axis 75

by which the beta magnitude is ascertained for the body; and the correction for beta unbalance will generate equal centrifugal forces radially directed from the longitudinal axis of rotation and separated angularly 180 degrees in a plane transverse to the longitudinal axis of rotation. At the same time the correction for alpha unbalance will generate a resultant centrifugal force equal and opposite to the unbalanced centrifugal force causing the alpha unbalance and the correction for the beta unbalance will generate centrifugal forces forming forces equal and opposite, that is, forming an algebraic sum of zero with the couple formed by the centrifugal forces causing beta unbalance.

A further characteristic of applicant's invention is that a numerical quantity determinative of alpha unbalance may be indicated by a proper machine simultaneously with an indication of a numerical quantity determinative of the correction to be made for beta unbalance, that is, the oscillation from which the alpha correction is ascertained, ascertains the numerical quantity determinative of the correction for alpha unbalance, even if simultaneously an oscillation is taking place at an angle thereto which is determinative of the correction to be made beta unbalance and vice versa. No correction whatsoever needs to be made in the correction planes until after the values for all corrections to be made have been ascertained, although if desired, alpha correction may be made and the beta magnitude ascertained. From this it follows, that if the corrections have been ascertained for both alpha and for beta unbalance, it will frequently occur that the correction for one kind of unbalance may be partially or fully cancelled by correction for the other; consequently both corrections may be effected by a single addition or subtraction of mass at one point in a particular plane and a single addition or subtraction of mass at a particular point in another plane.

As an embodiment of machine, applicant contemplates one in which the axis of oscillation, from which the numerical quantity determinative of the beta unbalance is obtained, will be in a transverse plane between a pair of planes in which correction for both alpha and beta unbalance is to be made. In case there are a plurality of pairs of correction planes, the position of the beta axis would be between the planes considered as pairs, that is, as many planes on one side as on the other.

The preferred embodiment would have the axis in a median plane to each pair. The ratio heretofore mentioned then becomes 1:1, so that after the numerical magnitude for correction for alpha unbalance has been ascertained it may be halved and one half applied in each correction plane, where there is a single pair, and the numerical quantity determinative of correction for beta unbalance may be halved and a half placed in each plane. If more than one pair of planes are used in which to make correction then the mass may be distributed equally in an amount determined by dividing the total mass change into as many equal parts as there are correction planes and applying one part in each plane. The correction for beta unbalance will be applied one half on one side of the longitudinal axis of rotation and the other half on the other side and could be distributed amongst those planes on one side of the median transverse plane in a ratio which would develop therein moments about the center axis used in determining the beta un-

balance of the rotor equal numerically to the turning moments generated by the distribution made in the correction planes on the other side of the axis.

The simplest and most convenient and preferred embodiment of a machine, where rotors of substantial length in proportion to their diameter are to be balanced, is to select two correction planes, position the beta axis midway between those planes and apply correction both for alpha and beta unbalance in these two planes.

As the essential point of novelty in the machine of applicant's invention is directed particularly to determining the numerical value of corrections to be made, the transverse planes in which they are to be made, the position of the correction mass in one plane as compared to that in the other, and the position of the alpha correction as regards the beta in a given plane, further data is needed to enable the determination of a resultant single mass change and its exact position in each plane.

The further data needed is the position of the "high point" and the "angle of lag". These are both well known and understood facts and both may be obtained by means which are old and well known. The high point and the angle of lag having been ascertained, the numerical quantities obtained by the oscillations caused by alpha unbalance and by beta unbalance are combined therewith as a matter of computation or graphically. The result of the method of treatment, whatever it may be, is that, in general, a single mass change for each of the correction planes is ascertained and its exact position in these planes as regards angular rotations about the longitudinal axis and radial distance therefrom. This change, when made, corrects unbalance in the rotor so that the rotor is then balanced both statically and dynamically.

Applicant's machine, as herein described, serves to determine numerical quantitative values which are usable together with other data such as the position of the high point and the angle of lag of the high point by which to determine by means of computation or graphically, as by a vector diagram, a resultant mass change, both in value and position, necessary in each of the correction planes. Applicant, therefore, designates, the use of data secured by his method as being "assigned", as it is used as a factor in computing the resultant mass change. The resultant mass change is dependent upon and is governed and determined by the data secured by applicant's method and machine.

In the balancing machine herein described in which provision is made for rotating a body about its longitudinal axis, and which is provided with means to permit oscillation about two axes, one of which is parallel to the axis of rotation of the body and the other of which is perpendicular to the axis of rotation, the unbalanced forces present in the body may be divided into two components, which are designated as the alpha component and the beta component respectively, and the beta component may be caused by a static unbalance or a dynamic unbalance or a combination of both static and dynamic unbalance. The alpha component is that part of the unbalance as a whole which causes the body to oscillate only about the axis parallel to the axis of rotation, and the beta component is that part of the unbalance as a whole which causes the body to oscillate only

about the axis perpendicular to the axis of rotation.

After the magnitudes of the alpha and beta components have been determined and the value of correction has been ascertained for making mass changes in the body as described herein, it will be found that the vector sum of the necessary mass changes on each end of the body is equal to the mass change that is necessary at each end to produce balance regardless of the means used to determine the necessary correction for unbalance. Therefore, if desired, the alpha and beta components for each end may be combined vectorially and a single mass change made on each end that will compensate for both the alpha and beta components.

In describing the invention, reference will be had to a particular physical embodiment of the machine and to the drawings thereof accompanying this specification, wherein like characters of reference designate like parts throughout the several views, and in which:

Figure 1 is a front elevational view of a device embodying the main principles of applicant's invention; Fig. 2 is a side elevational view of the device as shown by Fig. 1, viewed from the right hand side as shown in Fig. 1; Fig. 3 is a sectional elevational view on the plane indicated by the line III—III of Fig. 2, viewed in the direction of the arrows at the ends of the line; Fig. 4 is a top plan view of the device as shown by Fig. 1; Fig. 5 is a cross-sectional elevational view on the planes indicated by the lines V—V of Fig. 3, viewed in the direction of the arrows at the ends of the lines; Fig. 6 is a cross-sectional elevational view on the planes indicated by the lines VI—VI of Fig. 5, viewed in the direction of the arrows at the ends of the line; Fig. 7 is a cross-sectional view on the plane indicated by the line VII—VII of Fig. 6, viewed in the direction of the arrows at the ends of the line; Fig. 8 is a diagrammatic view illustrating an electric circuit and device included therein which may be used in connection with the invention; Figs. 9 and 10 are diagrams illustrating the mathematical relations underlying the invention; Figs. 11 and 12 are views of the left hand end and the right hand end respectively of the body shown by Fig. 10 after correction weights have been applied in the manner hereinafter described.

Broadly speaking, the particular physical embodiment selected by applicant to illustrate the principle of his invention, and illustrated in the drawings, includes: an electric motor, designated generally by M, well shown in Figs. 3 and 5, for driving purposes; a supporting frame designated generally by F, and well shown in Figs. 4 and 1, for supporting a body, B, to be balanced while that body is being rotated by the motor, M; indicating means, I, well shown in Figs. 6 and 7, simultaneously operative for exhibiting the extent of oscillation of frame F about each of two axes when a body to be balanced is supported thereby and is rotated by the motor M.

The specific embodiment of applicant's invention shown in the drawings provides a suitable case, within which and without which various members going to make up the device are supported, so that the device is what might be called self-contained.

Within the case I and formed, preferably integral with a wall thereof, as the front wall, are lugs, as 2 and 3, one of which, 2, is shown in Fig. 5, and both of which are shown in Fig. 6. Each

of these lugs is provided with a bore through which a pin, as 4, extends. On each of the pins, a motor supporting arm, 5, is journaled so as to turn freely therein. Each motor supporting arm, 5, is provided with spaced supporting lugs, as 6 and 7, cooperating with feet, as 8 and 9, of the motor M, and the lugs, as 6 and 7, and the feet 8 and 9, are fastened firmly together in any suitable or appropriate manner, as by cap-screws 10 and 11.

On the side of the motor remote from the connection of the motor supporting arms, 5, a bracket 12 is attached in any suitable and appropriate manner as by welding. This bracket has a substantial right angled extension 13 provided with an aperture 14. The aperture 14 receives a link 15 threaded throughout and provided with a flanged sleeve 16 on the upper portion thereof, as viewed in Fig. 5. Between the flange of the sleeve 16 and the extension 13 and surrounding the sleeve and bearing upon the flange and the extension 13 is a compression spring 17. Below the extension 13 is a threaded nut 18. The lower end of the link 15, as shown in Fig. 5, receives the end of a crank pin 19, which is also well shown in Fig. 3. Crank pin 19, as best shown in Fig. 3, is part of the crank arm 20 which is mounted rigidly upon a shaft 21 extending through the side of the casing I and journaled in a bearing 22 formed, preferably, integral with the casing I. The outer end of the shaft 21, that is, the right hand end as viewed in Fig. 3, is provided with an outstanding arm 23, shown in Fig. 3, and also shown in side elevation in Fig. 2. This arm has a handle piece 24 at the extremity remote from the shaft 21 and is formed with, preferably, a square aperture 25 in the end through which the shaft 21 is passed, corresponding with a square portion of the shaft 21 adjacent the end. Beyond the arm 23, the shaft 21 is threaded for the reception of a nut 26 which when screwed in place holds the handle member 23 firmly in place on the shaft 21.

By the construction just hereinbefore described the handle piece affords a means by which a manual operation may be performed to raise or lower the arm 23, as shown in Fig. 2, thereby oscillating shaft 21 and with it the crank 20 and crank pin 19 whereby link 15 is raised and lowered. When link 15 is raised, the motor M, as shown in Fig. 5, is raised, that is, when handle piece 24 is raised, the motor M is raised. When handle piece 24 is lowered, link 15 is lowered and the flanged sleeve 16 is drawn downwardly with link 15 compressing spring 17 against extension 13 of the member 12 attached to the motor M and so resiliently pressing the motor M downwardly.

Motor M has an armature, the shaft of which is designated 27, as best shown in Fig. 5. This shaft extends through the side of the casing I, and, within a pulley and belt guard 28 on the side of the casing I, bears a belt pulley 29, as best shown in Fig. 3. This pulley 29 serves as a driving means for a belt 30, as shown in Fig. 3 and Fig. 1, employed for driving the body B to be balanced. The belt 30, as best shown in Fig. 2, passes around the pulley 29, then under the body B and in contact therewith, then around a pulley 32 and back to pulley 29.

From the hereinbefore given description it will now be apparent that a body B to be balanced is in a position, as shown in Fig. 2, then if the handle piece 24 is lowered the pulley 29 will contact firmly with the belt 30 driving the same and

causing a rotative effort upon the body B or if handle piece 24 is raised, as shown in Fig. 2, then the pulley 29 will not bear sufficiently tightly upon the belt 30 to cause it to be driven and consequently the body B will not have a rotative effort exerted thereon and will become stationary and may be easily handled or manipulated.

The frame designated generally by F includes two parallel rods 33 and 34, as well shown in Fig. 5, in cross-section, and in end elevation in Fig. 2. Each of these rods is threaded on each end for receiving nuts as 35, 36, 37 and 38, as perhaps best shown in Fig. 4. Each rod has the inner raceway of a ball bearing belt pulley, guide or idler mounted thereon, as best shown in Fig. 2, in which the raceway on rod 34 for idler 31 is designated 39 and the raceway on rod 33 for idler 32 is designated 40. As best shown in Fig. 4, a cross arm 41 is provided apertured on each end for the reception of the rods 33 and 34. In order to position the cross arm 41 and hold it firmly in place and also position and hold firmly in place the inner races of the ball bearings 39 and 40, tubes are placed about the rods 33 and 34. The tubes placed about rod 34, which are exactly like those placed about 33, are two short pieces 42 and 43 between the inner race of the ball bearing member and two arms 44 and 45 which are apertured to receive the rod 34; another tube 46 between the arm 44 and the nut 35; and another tube 47 between the arm 45 and the end of the member 41. When nuts 35 and 37 are screwed tightly in place on the ends of the rod 34, the arm 41, the arms 44 and 45; and the inner ball race 39 are all held firmly in place so as to be free from longitudinal movement upon the rod 34. By an identical construction the other end of the member 41 through which rod 33 passes and the inner ball race 40 and arms 48 and 49 together with the tubes on the rod 33 are all held rigidly in place upon screwing on the nuts 36 and 38.

In order to support the body B to be balanced, stretchers 50 and 51, best shown in Fig. 4, are provided. These stretchers extend from side to side of the frame resting upon the tubes surrounding the rods 33 and 34 and are slidably longitudinal of the tubes. Each is provided with a half round bearing 52 as perhaps best shown in Fig. 2 for the reception of a shaft, as 53 of the body B to be balanced.

The frame F is supported by the arms 44, 45, 48 and 49. These arms as 48 and 49 are really the two legs of a U-shaped member provided with a slot, as 54, as best shown in Fig. 1. Through this slot 54 extends two leaf springs 55 and 56. Each spring is bent at a right angle so that a portion thereof, as 57 and 58, lies against the inside of the base of the U-shaped member. Above these turned over portions is a plate, as 59, pressed firmly against the turned over portions 57 and 58 and fastened rigidly in any suitable or appropriate manner as by welding to the arms 48 and 49. The lower ends of the spring members 55 and 56 extend down into a slot as 60 in the end of one arm of a two armed lever 61 as shown in Figs. 1 and 2. Two armed lever 61 is rigidly mounted upon the shaft 62 mounted in ball bearings 63 and 64 supported by the case 1.

As the frame F is supported at a point approximating its longitudinal center on the symmetrically formed two armed lever 61, the frame is free to oscillate in a vertical plane transverse to its length, that is, about the axis of the shaft 62,

that is, in the direction of the arrows 65 and 66 of Fig. 4. The frame F is also by reason of being mounted upon the flat springs 55 and 56, free to oscillate up and down in a vertical plane passed through the longitudinal axis of the body B to be balanced, that is, is free to oscillate, up and down about an axis transverse to the longitudinal axis in the direction of the arrows 67 and 68 of Fig. 3. It is, of course, understood that by the term "free to oscillate" hereinbefore used is meant free to oscillate against such restraint as is imposed.

If a body B to be balanced is supported by the stretchers as 50 and 51 and the belt 30 is adjusted under the body as shown and then the belt is caused to be driven by the motor M the body B will rotate about the longitudinal axis. If the body B is statically unbalanced then an oscillation of the frame F will be caused in the direction of the arrows 65 and 66. If the body is dynamically unbalanced then an oscillation of frame F will be caused in the direction of the arrows 67 and 68. If both static and dynamic unbalance are present in the body B then both oscillations will simultaneously take place.

The extent of oscillation caused by alpha unbalance is restrained by the flat spring 69, well shown in Figs. 3 and 5.

Spring 69 is attached to shaft 62 in any suitable or appropriate manner as by cap screw 70. The ends of the spring 69 extend in two directions substantially at right angles to shaft 62, as best shown in Fig. 5, and the ends thereof lie adjacent adjusting screws 71 and 72. By suitably adjusting the screws 71 and 72, a desired tension may be placed upon the spring 69 so that an alpha unbalance in the body B will cause a greater or lesser oscillation of the shaft 62.

The extent of oscillation caused by beta unbalance is restrained by flat springs 73 and 74, shown in cross-section in Fig. 3, and in side elevation in Fig. 5 and in end elevation in Fig. 1. The upper spring 73 is clamped between the plates 75 and 76 attached to arm 41 and the lower spring 74 bears upon the top of the right angled arm 77 attached, as by a cap screw 78, so as to rotate with and about the longitudinal center line or axis of the shaft 62. The outer ends of the springs as shown in Fig. 5 are held together by adjustable clamps as 79 and 80. These clamps can be approached nearer together or be separated farther apart thereby increasing or decreasing the reactive power of the springs 73 and 74.

If the frame F is caused to oscillate in the direction of the arrow 68, Fig. 3, that is, about an axis transverse to the longitudinal axis of the body B it is to a certain extent restrained by the action of springs 73 and 74 as spring 74 will bear upon the right angled arm 77 when the frame F moves in the direction of the arrow 68.

In order to exhibit the amount of oscillation caused by the alpha unbalance and the amount caused by the beta unbalance there have been provided an arm 81 extending out from shaft 62 and oscillatable with that shaft and an arm 82 pivoted on a bracket 83 intermediate its length and having one end positioned underneath and in contact with rod 84. The rod 84 is provided with threads 85' on its upper end and screws into a cavity in the arm 41 and is adjustable by the knurled finger piece 85 so that its lower end may be adjusted so as to lie exactly on the longitudinal center line of the shaft 62 when the belt 30 is not being driven.

To the free ends of each of the levers 82 and 75

81 is attached a thread like member, as 86 and 87, respectively. Each of the thread like members, as 86 and 87, passes several times about a small shaft, as 88 and 89, respectively, best shown in Fig. 7, and the end of each is attached to tension springs, as 90 and 91, respectively. The shafts 88 and 89 are each suitably mounted for oscillation, as by having their ends formed conical and resting in conical depressions in members such as 92 and 93. Each shaft, as 88 and 89, has arms, as 94 and 95, respectively, extending substantially at a right angle thereto and each arm is continued by a pointer, as 96 and 97, respectively, forming a visible indicator.

15 The construction last above described is such that an oscillation of shaft 62 causes an oscillation of arm 81 and a movement of thread 87 which being wound about shaft 89 causes that shaft to rotate and the arm 95 and pointer 97 carried thereby to be oscillated. In the same way a vertical oscillation of the left hand end of the frame F, as viewed in Fig. 3, causes the rod 84 to move downwardly and oscillate lever 82 which by reason of being connected with thread 86 causes an oscillation of shaft 88 and the arm 94 and the pointer 96 connected therewith. The pointers 96 and 97 may be viewed through an aperture in the front of the casing as shown in Fig. 1 and by the extent of their movement so may the value of alpha and beta unbalance in the body B to be balanced, be determined.

35 As the pointers 96 and 97 will be in a continual state of oscillation when the device is in use for ascertaining the unbalance of a body, it would be a rather difficult matter to determine accurately by the eye alone the extreme swing of the pointers 96 and 97. To the end of facilitating determining the extreme swing of the pointers 96 and 97, applicant has provided pivoted sectors, as 98 and 99, adjacent each of the pointers, as 96 and 97, and has graduated the edges of these sectors 98 and 99 adjacent the pointers 96 and 97, as indicated by Fig. 1 by 100 and 101. On each of the sectors cooperating electrical contacts as 102 and 103 have been mounted. When a body B to be balanced is in motion and is causing an oscillation of arm 95 or arm 96 or both, a button 104 attached to sector 98 is grasped by the fingers and moved so as to bring the end of contact 102 closer and closer to arm 94 until a point is reached where the arm 94 contacting with 102 causes a separation of the contacts 102 and 103. This marks 55 the extreme oscillation of the arm 94 and pointer 97. In the same way the button 105 is moved until the arm 95 just breaks the electric contact associated therewith. The breaking of an electrical contact may be indicated, as shown in 60 Fig. 8, wherein a small lamp 106 is shown connected in circuit with the contacts 102 and 103 and a source of potential 101. When the proper adjustment of a sector as 98 is made the lamp will be extinguished upon each oscillation of the pointer or arm 94 in the direction towards the contact 102. This contact member 102, of course, must be made of such size that it will not materially interfere with the free swing of the arm 94, that is, it must be extremely sensitive 65 so as to require but very little appreciable force to operate it.

After the exact adjustments of the sectors as 98 and 99 are obtained to indicate the extreme swing of the arms as 94 and 95 then after the 75 motor M has been freed from driving belt 38 by

a manipulation of the hand piece 24 the sectors as 98 and 99 will be in such position that the extreme swing of the pointers as 96 and 97 which occurred is indicated by the amount of displacement of the sectors as 98 and 99 from an arbitrary zero position.

Applicant contemplates using a motor M of constant speed. He also contemplates so positioning the body B to be balanced that correction planes 108 and 109 will be positioned one 10 on one side of the median line 110 and the other on the other side thereof and each at the same distance from the median line and this median line, as shown in Fig. 1 is in the vertical plane passing through the axis transverse to the longitudinal axis of the frame F about which oscillation in the direction of the arrows 67 and 68 takes place. Applicant further contemplates, in the particular machine shown, having longitudinal axis 111, of the shaft 27 of the body B to be 20 balanced, parallel to the longitudinal axis 112 of the shaft 62.

With all parts of the device arranged as shown in the drawings a body of known characteristics as regards alpha and beta unbalance 25 and provided with means for altering the magnitude of the static and beta unbalance may be mounted upon the stretchers 50 and 51 and then caused to rotate by depressing the handle piece 24. Readings may then be taken of the displacement of the sectors 98 and 99 for a wide range of known changes in the magnitude of alpha and beta unbalance in the body of known characteristics and from these readings the device may be calibrated so that upon placing a 35 body as B in the device and rotating it and observing the necessary displacement of sectors 98 and 99 the numerical magnitude of both alpha and beta unbalance in the body B may be ascertained. By a single mounting of the body or 40 rotor, the necessary desired numerical magnitudes of both alpha and beta unbalance are determined as the body or rotor simultaneously oscillates with two degrees of freedom about two axes.

The mathematical relations which have to be observed when applying corrections determined by the use of the machine and the general mathematical relations which subsist and which exemplify the principles underlying the invention are illustrated by the diagrams Figs. 9 and 10. Fig. 9 illustrates the general case. Fig. 10 illustrates the special case paralleling the arrangement of the specific embodiment shown in the drawings.

In Fig. 9, B' indicates the unbalanced body; DA designates the beta axis; LA designates the longitudinal axis, and may also be considered to represent the alpha axis. If the body B' is oscillated and numerical results determinative of both alpha 60 and beta unbalance obtained, then after correction the correction masses will bear proper relation to one another as centrifugal forces. The correction mass CF₁ considered as a centrifugal force added to the correction mass CF₂ considered 65 as a centrifugal force will equal the original unbalanced alpha centrifugal force, that is,

$$CF_1 + CF_2 = CF_{\alpha}$$

The moments generated by these centrifugal 70 forces about the beta axis will bear the following relation: $CF_{1\alpha}X = CF_{2\alpha}Y$. The above equations illustrate the disposition and relation of the masses causing centrifugal forces which counter-balance the unbalanced alpha centrifugal force 75

but do not themselves create an unbalanced beta force.

The masses determined by oscillation applied to body B' to compensate beta unbalance are CF₃ and CF₄. These masses considered as centrifugal forces have a relation which may be expressed by a formula as follows: $CF_3Xa + CF_4Xb =$ original beta couple unbalance. These masses considered as centrifugal forces also bear the following relation: $CF_3 = -CF_4$. The foregoing equations and mathematical relations not only illustrate how correction masses are to be applied but also illustrate the fundamental relations which must subsist, as hereinbefore pointed out, in order that a correction mass may be applied for alpha unbalance without generating a beta unbalance and how a beta unbalance correction may be applied without generating an alpha unbalance.

In Fig. 10 the mathematical relations which subsist with the preferred special form of the invention as illustrated by the drawings is employed. When this special form is used the beta axis DA is positioned midway between the correction planes CP and CP', that is, $x=y=a=b$ and $R=R'$. Under such conditions calculations and corrections may be made on the basis of weight rather than centrifugal force. $W_1=W_2$ and $W_3=W_4$.

In the particular arrangement shown in the drawings the magnitude or mass change necessary to correct the body B for alpha unbalance would be halved and one half assigned to each correction plane as 108 and 109. The magnitude or mass change necessary to correct for beta unbalance would also be halved and one half placed in the correction plane 108 and the other half placed in the correction plane 109. When making correction for alpha unbalance all of the mass changes would be made on one side of the longitudinal center line and in a line parallel thereto. When making correction for beta unbalance one portion would be placed on one side of the longitudinal center line and the other portion on the other side of the longitudinal center line and on the other side of the transverse axis upon which oscillation takes place to determine the extent of beta unbalance and correction mass in one plane would be angularly 180 degrees from the position of the correction mass in the other plane, that is, if the beta correction mass were placed in the correction plane 108, in the plane of the paper at the upper right hand corner of body B as shown in Fig. 10, then the other correction mass for beta unbalance would be placed, in the plane of the paper, in correction plane 109 at the lower left hand corner of the body B as viewed in Fig. 10.

Applicant's device does not determine what is technically known as "high point" or "angle of lag". It merely determines the numerical magnitudes necessary to correct for unbalance. Before any mass change may be made to correct for unbalance the high point and angle of lag must be determined. This may be done by well known and approved methods thoroughly understood by those skilled in this art. These having been determined the numerical magnitudes ascertained by applicant's device are then distributed in the two correction planes in accordance with the determined high point and angle of lag. As there are two masses in each correction plane, one for alpha and the other for beta unbalance, it is perfectly feasible before actually applying any correction mass by computation as vectorially, to ascertain a single resultant correction mass for

each plane and then apply a mass in accordance with this resultant in each plane.

By applicant's device a single positioning of a body to be balanced is made and after that positioning a rotation thereof is caused from which data is secured sufficient to ascertain in connection with the high point and angle of lag the necessary mass changes in the body and the position thereof in order to balance the body both statically and dynamically and the instrument readings by which the magnitude is ascertained persist so that they may be read at leisure, as the rotational displacement of two bodies, both of which are stationary at the time of reading. In order to actually balance a body which is in unbalance it is necessary to determine the high spot, angle of lag, and magnitude of the unbalance.

In order to determine the high spot, the body is mounted in the frame F just as the body B is mounted. While the body is moving freely about both the alpha and the beta axes, a scribe is placed lightly against the shaft of the body in a horizontal plane at one end of the rotating shaft. This will make a mark on the shaft which is indicative of the high spot. This high spot will be the high point for the alpha unbalance. In order to obtain the high spot for the beta unbalance the scribe would be placed in a vertical plane, preferably at the other end of the shaft in order to avoid confusion with the alpha high spot and the scribe caused to lightly touch the shaft whereupon a mark will be made indicative of the high point for beta unbalance.

In order to determine the angle of lag, it is to be remembered that the body is mounted resiliently, that is with a minimum damping, consequently, the angle of the high spot behind the actual heavy spot, commonly referred to as the lag angle, is easily ascertained. If the body to be balanced is being rotated at a speed appreciably lower than the resonant frequency of the system, the lag angle is zero. If the speed of the body is at the critical point, that is, at the resonant point the angle of lag is 90 degrees. If the speed of the body is higher than the resonant speed the angle of lag is 180 degrees. In a spring suspended system of the type used in this invention, the change in lag angle as resonance is approached and passed through, is very abrupt, so abrupt in fact that in practical production balancing even where a high degree of accuracy is desired this lag angle is always taken at zero at speeds below resonance and at 180 degrees at speeds above resonance. It is impractical to take high spot readings at resonance since this is the critical point and the percentage change in lag angle is extremely large for a very small percentage of change in speed either above or below the critical or resonant speed. The resonance mentioned above is readily detected by the extreme or maximum vibration which is evidenced when the body is rotated. This may be and usually is observed by the unaided eye. The speed is generally increased until it is greater than the resonant speed and then the driving power is shut off and the body allowed to coast to a stop. The going of the body through the critical or resonant speed is readily observable by the amplitude of vibration.

The magnitude of unbalance is obtained by measuring the linear displacement of the rotating body as by members 86 and 87 or pointers 96 and 97. By calibrating, this linear measurement can be reduced to inch ounces. In a case where substantially identical bodies are to be balanced the

application Serial No. 431,719, filed February 27, 1930.

What I claim as new and desire to secure by Letters Patent of the United States, is:

1. In a balancing machine, in combination: a shaft mounted for oscillation; resilient means restraining oscillation of the shaft; a frame supported by the shaft; resilient means between the frame and the shaft allowing oscillation of the frame about an axis at a right angle to the axis of the shaft; a third resilient means uniformly restraining the last mentioned oscillation of the frame in any oscillated position of the shaft; a member attached to the frame and terminating at the longitudinal center line of the shaft prolonged when the frame is at rest in unoscillated position; means actuated by said last named member for indicating the extent of oscillation of the frame; a member attached to the shaft; means actuated by said last named member for indicating the extent of oscillation of the shaft; and means for supporting on the frame a body to be balanced and rotating it whereby oscillations of the shaft and the frame will be caused and the extent of such oscillations are usable in calculating the mass changes necessary to balance the body.

2. In an indicator for a balancing machine, in combination: a first pivoted pointer; a second pivoted pointer; means for pivoting each pointer in one direction by oscillations caused by the rotation of an unbalanced rotating body; means for returning each pointer to initial positions; a pivoted sector adjacent each pointer, shiftable over substantially the arc of movement of the adjacent pointer; a set of cooperating electrical contacts on each sector, each set having an arm lying in the path of movement of a pointer when a sector is properly adjusted; electrical circuits for each set including an electrically energizable device and a source of energy whereby when the pointers are oscillated and the sectors are properly adjusted the cooperating contacts are operated to influence the electrically energizable device informatively whereby the extent of oscillation of the pointers is ascertained.

3. In a balancing machine, in combination: means for rotating a body to be balanced; a frame for supporting the body to be balanced while it is rotating; means allowing the frame to oscillate restrainedly simultaneously on two axes one at a right angle to the other, one axis being between and at known distances from at least two correction planes of the body; means simultaneously acting for indicating the extent of movement on each axis whereby data usable in correcting the body for unbalance is obtained.

4. In a balancing machine, in combination: a shaft mounted for restrained oscillation; a frame supported by the shaft; means for supporting a body to be balanced for rotation on the frame; means for driving the body; means allowing the frame to oscillate restrainedly simultaneously with the oscillation of the shaft on an axis at a right angle to the axis of the shaft, said last mentioned axis positioned between and at known distances from at least two correction planes of the body; means for simultaneously determining the extent of oscillation of the shaft and the oscillation of the frame at a right angle to the axis thereof when the body is rotated whereby data usable in correcting the body for unbalance is obtained.

5. In a balancing machine, in combination: a shaft mounted for oscillation; a frame supported

calibration may be in terms of weights which may be placed in the balancing planes at a given radius from the axis of rotation. The calibration may be accomplished mathematically from static measurement of the mass of the system and elasticity of the springs or more practically by placing a body in the machine, making high spot and alpha and beta unbalance reading and then known test weights being applied at known points and the reduction in vibration produced by the known weights noted. Since the restraining springs have a straight line elastic characteristic the calibration curve is a straight line and therefore only two points are necessary to draw the curve.

If a body such as that shown by Fig. 10 is to be balanced and the correction planes are the planes of the ends of the body, the body would be placed in the machine as shown by Figs. 1 to 8 inclusive and rotated and the alpha reading and the beta reading are both 10 units on the scale as indicated by the pointers 96 and 97. The readings are taken above resonance therefore the lag angle is 180 degrees and the high spots are the light spots, the angular location of the high spots would be determined by a scribe as hereinbefore pointed out, the alpha high spot by a scribe in a horizontal plane and the beta high spot by the scribe in a vertical plane. Since the body was placed in the machine with the beta axis midway between the end planes of the body all of the data is now obtained by which to balance the body.

In Figs. 11 and 12 are shown two views of the ends of the body as shown by Fig. 10 but both ends are viewed from the same end. In Fig. 11, 111 designates the correction weight of five units applied to the left hand of the body shown in Fig. 10, at the alpha high spot, or light spot. In Fig. 12, 112, 113 designates a correction weight of five units applied to the right hand end of the body shown by Fig. 10 at the alpha high spot or light spot. In Fig. 11, 114 designates a beta correction weight of five units applied to the left hand end of the body as shown by Fig. 10 at the beta high spot or light spot.

The other weight of the beta couple is applied 180 degrees from the weight 114 at the other end or right hand end of the body 10 and is designated 115.

It will be noted that the alpha correction weights have been so located with respect to the beta axes that the couple created by these weights about the beta axis is zero, therefore the beta component of unbalance in the body has not been disturbed by applying the correction of alpha unbalance. In the same way, the correction for beta unbalance has been divided between the correction planes to produce a balancing couple without introducing any change in the unbalance of the body as respects the alpha axis. Since the body has been balanced for both alpha and beta components and is suspended with two degrees of freedom, it will be in balance when rotated in any type of suspension.

Although I have particularly described the principle of operation and construction of a particular physical embodiment of my invention, nevertheless, I desire to have it understood that the particular physical embodiment selected is merely illustrative and does not exhaust the possible physical embodiments of the idea of means underlying my invention or the physical embodiments by which my invention may be practiced.

75 This application is a division of my copending

by the shaft; means for supporting and rotating a body to be balanced on the frame; means connecting the shaft and the frame whereby the frame may oscillate about an axis at a right angle to the axis to the shaft, said last mentioned axis being between and at known distances from at least two correction planes of the body; resilient means for restraining the said oscillation of the frame; means attached to the shaft and oscillatable therewith for bearing against the said resilient means whereby the said resilient means is tensioned uniformly for all positions of the said shaft.

6. In a balancing machine, in combination: a motor; means for rotating a body to be balanced driven by the motor; a frame for supporting the body to be balanced while it is rotating; means allowing the frame to oscillate restrainedly simultaneously on two axes one at a right angle to the other, one of said axes being between and at known distances from at least two correction planes of the body; means simultaneously acting for indicating the extent of movement on each axis whereby data usable in correcting the body for unbalance is obtained.

7. In a balancing machine, in combination: a housing; orificed lugs attached to the housing; pins, one passing through an orifice of each lug; supporting arms, each supporting arm formed with an orifice at one end and a plurality of spaced orificed lugs at the other end, each supporting arm being pivoted on one of the said pins; a motor provided with lugs matching the lugs of the arms and orifices for fastening thereto by screw-like means and screw-like means for such attachment; a bracket attached to the motor; a link resiliently attached to the bracket; a crank connected to the link; and means for operating the crank whereby the motor is oscillated; a belt pulley driven by the motor; a belt driven by the belt pulley; a frame having two degrees of free-

dom and provided with means for supporting a body to be balanced; and means for guiding the belt in contact with the body to be balanced whereby the body to be balanced is rotated.

8. In a balancing machine, in combination: 5 means for rotating a body to be balanced; a frame for supporting the body to be balanced while it is rotating; means allowing the frame to oscillate restrainedly simultaneously on two axes one at a right angle to the other, and one axis between and at known distances from at least two 10 correction planes of the body; means simultaneously acting for indicating the extent of movement on each axis whereby data usable in correcting the body for unbalance is obtained.

9. In a balancing machine, in combination: 15 means for rotating a body to be balanced; a frame for supporting the body to be balanced while it is rotating; means allowing the frame to oscillate restrainedly simultaneously on two axes, one at a right angle to the other, one of said axes being between two arbitrary planes of the body within which correction for unbalance is to be made and at known distances therefrom; and means simultaneously acting for indicating 20 the extent of movement on each axis whereby data usable in correcting the body for unbalance is obtained.

10. In a balancing machine, in combination: 25 means for rotating a body to be balanced; a frame for supporting the body to be balanced while it is rotated; means allowing the frame to oscillate restrainedly simultaneously on two axes, one at a right angle to the other, one axis being between and at known distances from at least two 30 correction planes of the body; means manually controllable for indicating the extent of movement on each axis whereby data useable in correcting the body for unbalance is obtained.

40 STANLEY D. LIVINGSTON.
